UNITED STATES PATENT OFFICE.

RUDOLPH HANAU, OF NEW YORK, N. Y., ASSIGNOR TO THE AUTO PAPER FEEDER COMPANY, OF NEW YORK, N. Y., A CORPORATION OF NEW YORK.

SHEET-SEPARATOR FOR PAPER-FEEDING MACHINES.

986,384.

Specification of Letters Patent.

Patented Mar. 7, 1911.

Application filed June 25, 1909. Serial No. 504,248.

To all whom it may concern:

Be it known that I, RUDOLPH HANAU, a British subject, residing in the borough of Manhattan, city, county, and State of New York, have invented certain new and useful Improvements in Sheet-Separators for Paper-Feeding Machines, of which the following is a full, clear, and exact disclosure.

My invention relates to that class of paper feeding machines in which the sheets are taken from a pile one at a time and fed to other mechanism such as a printing press or folding machine.

The separator itself comprises a fixed lower plate coöperating with a movable upper member, both of which have contacting surfaces with different frictional characteristics, the upper member usually having greater frictional engagement with the sheets of paper than the lower plate.

The object of my invention is to generally improve and simplify the construction of paper feeding machines so that the same are not only more efficient but more accurate in operation when running at high speeds.

By the construction which I have devised the top sheet of a pile of sheets being fed to a printing or folding machine is moved positively and accurately at precisely the right time and its tendency to adhere to a lower sheet or sheets is obviated. This is accomplished not only by a more positive and accurate movement of the movable frictional feeding member but also by means for maintaining the lower sheets stationary while the upper sheet is being advanced.

Heretofore in the employment of fixed or movable members having frictional surfaces the lower member or plate has been so arranged or constructed that the same amount of friction has been produced over the entire length of the plate. When the top sheet of paper is carried over the edge of the second sheet, the sudden retarding action of the lower plate tends to cause the top sheet to come suddenly to a stop owing to the fact that the friction of the lower member is applied all at one time. This tends to hinder the efficient action of the machine as it tends to cause the upper reciprocating member to slide on the paper.

One object of my invention therefore is to overcome this difficulty by providing a plate on which the friction is gradually increased from the time the sheet enters the space be-

tween the separating members until it reaches the opposite end thereof.

My invention also comprises certain improved mechanism for raising and lowering and reciprocating the upper separating member and also means coöperating therewith for holding the second sheet of the pile and the other lower sheets more positively in position while the upper sheet is being advanced.

For a detailed description of the several embodiments of my invention, reference may be had to the following specification and to the accompanying drawings forming a part thereof, in which—

Figure 1 is an elevation of the complete feeding mechanism, the lower separating member being shown in cross-section; Fig. 2 is a plan view of one side thereof; Fig. 3 is an elevation of the separating mechanism shown near the end of a stroke as it advances toward the left; Fig. 4 is a plan view of the same; Fig. 5 is a perspective view of the upper and lower feeding members, showing the relative position of the parts at the beginning of a stroke toward the left; Fig. 6 is a longitudinal sectional view of the upper feeding member showing its manner of attachment to the supporting rod or shaft; Fig. 7 is a plan view of modified form of the lower block or pad; Fig. 8 is a longitudinal sectional view thereof; Fig. 9 an end view thereof showing the means for attaching the pad to the frame of the machine; Fig. 10 is a plan view of another modification, while Figs. 11, 12 and 13 are respectively a longitudinal sectional view, a transverse sectional view and an end view of the same.

I have not considered it necessary to illustrate all the details of the paper feeding mechanism which receives the paper from the separating mechanism, inasmuch as they will be readily understood by one skilled in the art, especially when considered in the light of the prior patent issued on the application of J. Kleidmann, No. 911,132, on February 2nd, 1909, over which the device of the present application is an improvement.

Referring to the drawings, 1 indicates a pile of paper to be fed to the feeding mechanism and to printing or folding mechanism, and which is retained in position at its forward end by a plate or platen 2, the upper

end of which terminates in a horizontal shelf 3. The lower member or plate 4 of the separating device is attached to the shelf 3 by means of a thumb-screw 5. As shown in Fig. 5, this plate is provided with a contact surface 6 preferably of rubber which has a gradually increasing frictional resistance from the right end to the left end of the plate. This may be accomplished in several ways but in Fig. 5 I have indicated the rubber surface as being harder at the right end of the plate than at the left end. This variation in the character of the rubber may be brought about during vulcanizing, the softer part of the plate being vulcanized to a less degree than the harder part, or otherwise treated so as to produce the desired result. It should be noted that the variation in the frictional resistance is accomplished by changing the character or hardness of the material of the surface, or in other words, by varying its coefficient of friction.

In Figs. 7 to 13, inclusive, I have shown two other modes of accomplishing this result. In Figs. 7 to 9 inclusive the surface of the plate is divided into three triangular portions 7, 8 and 9. The triangular portion 9 is of softer material than the triangular portions 7 and 8 and gradually diminishes in width as it approaches the right hand end of the plate. This arrangement gives substantially the same effect as with a single plate having its surface as a whole treated so as to produce the gradually increasing frictional resistance. Figs. 10 to 13 show the plate as consisting of two parts 10 and 11, the latter being placed upon the former and offering less frictional resistance than the part 10. In this form the triangular portion 11 may be a plate of metal or similar material superposed on the plate 10 and having a less frictional resistance. It is obvious that the relative parts for varying frictional resistance from one end of the plate to the other may be arranged in various ways, and I have illustrated the arrangements shown simply as examples thereof.

Referring now to Figs. 1 and 2, the numeral 12 indicates the upper separating member in the form of a rubber covered roll which is carried at the ends of two forwardly projecting arms 13. The arms 13 are pivoted on a horizontal shaft 14, which is mounted in movable bearings 15 which slide upon horizontal guide rods 16. To one of the supporting arms 13 for the roll 12 is pivoted a pawl 17, which is adapted to engage a ratchet wheel 18 on one end of the roll 12. The pawl 17 has a downwardly projecting arm 19 which is for the purpose of contacting with the top sheet thereby maintaining the pawl 17 out of engagement with the ratchet wheel 18 until the roll 12 has advanced far enough toward the left

to allow the arm 19 to drop from the forward edge of a sheet and thereby cause the roll to stop rotating. The friction of the roll will then advance the paper until the end of the stroke of the separating mechanism has been reached. The shaft 14 also has pivoted thereon a rearwardly projecting arm 20, and said arm is connected with the shaft 14 through a spring 21 which is rigidly attached to the shaft 14 by the fixed collars 22, the central portion of the spring resting upon the arm 20 as indicated in Fig. 2. This spring 21 always has a tension tending to rotate the shaft 14 so as to force the roll 12 downward and keep it in engagement with the top sheet of the pile of sheets being fed through the machine. The arm 20 is preferably composed of two telescoping parts so that its length may be adjusted according to the width of different sheets of paper, said parts being held in their relative position by means of a set screw 23. The axle of the roll 12 supports two rearward extending arms 55 which carry a weighted roll 56 preferably of heavy metal. This roll is for the purpose of producing a pressure through the top sheet upon the second and subsequent sheets to aid in preventing them from sliding forward with the top sheet.

In Figs. 5 and 6 I have shown the details of the upper part of the separating mechanism including an auxiliary means by which the roll 12 is forced into engagement with the paper. This comprises a compression spring 50, one end of which bears upon the bar 51, while the upper end thereof bears against a set screw 54 in the end of the arm 52 fixed on the sleeve 53. This allows tension of the compression spring 50 to be adjusted to any desired degree independently of the spring 21. The sleeve 53 is carried by the shaft 14 so as to be slidable longitudinally thereon. This is accomplished by providing a key-way 57 in the shaft 14 in which a key 58 is seated. The key 58 also engages a slot 59 in the bushing 60 and is retained in position by means of a set screw 61 passing through the sleeve 53. The bushing 60 is provided with extensions at its end as indicated at 62 which are for the purpose of supporting the ends of the arms 13 pivotally in position. This arrangement allows the upper separating roll 12 to be adjusted to any desired position transversely of the machine and at the same time allows the requisite pressure to be produced thereby. A slot 63 in the eye of the arm 13 cooperates with a limiting pin 64 on the sleeve 53 and determines the arc of movement of the roll 12 about the axis of the shaft 14. If desired, however, this auxiliary tension device including the spring 50, bar 51, arm 52 and screw 54 may be omitted, in which case the arms 13 are rigidly attached to the sleeve 53. The pres-

sure of the separating member 12 is then determined by the tension of the spring 21 alone. The rear end of the arm 20 carries a roller which has a central reduced portion 24, and two enlarged end portions 25. In the path of the motion of the enlarged portions 25 of the roller is a sheet 26 of rubber or similar flexible frictional material, which is centrally connected with a horizontal arm 10 27 pivoted on a rod 28 at the rear of the machine. The roll 25 and the flexible sheet 26 constitute an additional means for holding all except the top sheet of paper in position and act in a way similar to the roll 56 except that the roll 25 acts through the flexible sheet 26 instead of through the top sheet of paper as does the roll 56. The roller 25 travels back and forth upon the sheet of flexible material 26 and the distance between 15 the contacting point of the roller 25 and the contacting point of the roll 12 is so adjusted that the roller 25 follows and will always be just beyond the rear edge of the top sheet, and since the arm 20 is depressed by the spring 21 the roller 25 will cause the sheet 26 to bear upon all of the sheets of the paper except the top one, which will be free to move under the influence of the advancing roll 12. In this manner pressure is 20 brought to bear upon all of the sheets except the one which is to be advanced to the printing or folding mechanism. The sheet 26 being stationary, it will not tend to cause the second sheet to move as would the roll 25 if it contacted directly with the paper. This is clearly illustrated in Figs. 3 and 4. It should be noted that the central reduced portion 24 of the roller may engage and travel on the arm 27. This is for the purpose of preventing said roll from dropping below the edge of the paper when its reciprocating motion extends to a point toward the right beyond the rear edge of the pile. A transverse reciprocating motion is 25 given to the shaft 14 by means of a connecting rod 29 pivotally carried thereon, the opposite end of which is connected with the crank 30 mounted on the shaft 31. The outer end of the shaft 31 carries a sprocket 30 wheel 32 over which passes the sprocket chain 33. This sprocket chain also passes over two other sprocket wheels 34 and 35. The shaft 36 on which the sprocket wheel 34 is mounted carries a cam 37, which cooperates with the follower 38 mounted on the end of a lever 39. The lever 39 is mounted on a transverse shaft 40 which carries the arms 40' to support the roller 41, which forms the pressure roller for causing 30 the sheets to be advanced from the separating mechanism. The driving roller 42 is carried on the shaft 43 which is driven by a pulley or similar power transmitting device (not shown). The sprocket wheel 35 35 is attached to the shaft 43 thereby driving

the sprocket chain 33 and rotates continuously.

The roller 12 must be lowered and raised in order to engage and disengage the top sheet of the pile of sheets, and I have provided the following mechanism for accomplishing this result. The shaft 14 carries two laterally extending arms 44 and 45. The end of the arm 44 is located beneath a set screw 46 carried on the connecting rod 29, while the end of the arm 45 carries a set screw 47 adapted to engage a lug 47' carried by the slideable bearing 15. When the crank 30 is rotating in the direction indicated by the arrow in Fig. 1, the connecting rod 29 will have a transverse motion downward from the position of the crank pin shown and when the crank has reached a horizontal position the end of the set screw 46 will engage with the arm 44 and since this arm is rigidly connected with the shaft 14, it will raise the arms 13 of the roll 12, so that the latter will be disengaged from the paper. It should be noted that this will occur at the end of a stroke toward the left and since the motion of the crank pin in a vertical direction is greatest at this point, the raising of the roll 12 will be accomplished very positively and quickly. Thereafter the arm 44 will continue to be depressed until the crank has rotated 180° at which point the arm 44 moves upward and the roll 12 downward onto the paper to begin another stroke toward the left. Since the pin 63 limits the motion of the roll 12 as regards the shaft 14, the limit of downward motion of the roll 12 may be regulated by the set screw 47 on the arm 45. It should also be noted that at this point the crank pin of the crank 30 is moving upward and has the greatest vertical velocity so that the roll 12 is quickly and positively brought into engagement with the paper, while at the same time the horizontal reciprocation of the parts has ceased. This reciprocating motion and the engagement of the roll 12 with the paper at the beginning of a stroke and its disengagement at the end of a stroke will be continued as the crank 30 continues to rotate.

Having thus described these forms of my invention, what I claim and desire to protect by Letters Patent is:

1. In a sheet feeding mechanism, a reciprocating separating member, means for reciprocating said member, a horizontally fixed sheet of flexible material adapted to rest on the pile of sheets being treated, a pressure device adapted to rest upon said sheet of flexible material and means for reciprocating said pressure device.

2. In a sheet feeding mechanism, a reciprocating separating member, means for reciprocating said member, a following roll, means for reciprocating the same with the

130

- said reciprocating member, and a horizontally fixed sheet of flexible material adapted to rest on the pile of sheets being treated and on which said roll is adapted to reciprocate.
3. In a sheet feeding mechanism, a reciprocating separating member, means for reciprocating said member, a following roll connected with said reciprocating means, a sheet of flexible material adapted to rest upon the pile of sheets being treated, a support connected with said sheet of flexible material, said following roll being adapted to rest upon said sheet of flexible material during a portion of its stroke and upon said support for the remainder of its stroke.
4. In a sheet separating mechanism, a reciprocating separating member, means for reciprocating said member comprising a reciprocating carriage, a crank, a connecting rod between said carriage and crank, and an arm adapted to be depressed by the transverse motion of said connecting rod for raising said reciprocating member.
5. In a sheet separating mechanism, a reciprocating separating member, means for reciprocating said member comprising a reciprocating carriage, a connecting rod pivoted thereto, a crank for driving said connecting rod, a stop carried by said connecting rod, and an arm connected with said separating member and adapted to engage said stop to raise said member during a stroke in one direction.
6. In a sheet separating mechanism, a reciprocating separating member, means for reciprocating said member comprising a reciprocating carriage, a connecting rod pivoted thereto, a crank for driving said connecting rod, a stop carried by said connecting rod, an arm connected with said separating member and adapted to be engaged by said stop to raise said separating member, a second arm connected with said separating member and a stop adapted to engage said second arm to limit the downward motion of said separating member.
7. In a sheet separating mechanism, a reciprocating separating member, a carriage to which said member is attached, means for reciprocating said carriage, a rearwardly extending arm pivoted to said carriage, a support for the outer end of said arm, and a spring connected with said arm for forcing said separating member downward.
8. In a sheet separating mechanism, a reciprocating separating member, a carriage to which said member is attached, means for reciprocating said carriage, a rearwardly extending arm pivoted to said carriage, a roll at the outer end of said arm and adapted to produce pressure on the pile of sheets, and a spring connected with said arm and said member for forcing them downward.
9. In a sheet separating mechanism, a reciprocating carriage, an arm pivoted thereto, a roll carried at the outer end of said arm, a sheet of horizontally fixed flexible material upon which said roll rests and a spring connected with said arm and with said carriage for forcing said arm downward.
10. In a sheet separating mechanism, a reciprocating separating member, means for reciprocating and raising and lowering said member, a spring connected between said member and said reciprocating means for producing a downward pressure on the former and a supplementary adjustable spring between said member and said reciprocating means.
11. In a sheet separating mechanism, a reciprocating separating member, a carriage therefor, means for reciprocating said carriage and for raising and lowering said member, a spring carried by said carriage for producing a downward pressure on said member and a supplementary adjustable spring connected with said member for regulating its pressure.
12. In a sheet separating mechanism, a reciprocating separating member, a carriage therefor, means for reciprocating said carriage and for raising and lowering said member, a rearwardly extending arm pivoted to said carriage, a pressure roll at its outer end, a spring connected between said carriage and said arm for forcing said member and said roll downward, and an auxiliary adjustable spring connected with said member for regulating its pressure.
13. In a sheet separating mechanism, a reciprocating separating member, a transverse shaft, means for reciprocating said shaft longitudinally of the machine and for oscillating the same, a rearwardly extending arm pivoted on said shaft, a roll at the end of said arm, a spring connected between said shaft and arm, arms pivoted on said shaft and on which said separating member is carried, and an auxiliary adjustable spring for regulating the pressure of said member.
14. In a sheet separating mechanism, a reciprocating separating member adapted to have fixed contact with a sheet, and a freely rotatable following roll connected therewith and adapted to rest on the paper immediately in the rear of said separating member.
15. In a sheet separating mechanism, a reciprocating separating member adapted to have fixed contact with a sheet, and a freely rotatable following roll carried thereby and adapted to rest on the paper immediately in the rear of said separating member.
16. In a sheet separating mechanism, a separating member having a frictional surface varying progressively in frictional resistance from one end to the other.

17. In a sheet separating mechanism, a separating member having a frictional surface which increases in frictional resistance from one end toward the other.
- 5 18. In a sheet separating mechanism, a separating member having a contact surface of gradually increasing frictional resistance from one end toward the other.
- 10 19. In a sheet separating mechanism, a stationary separating member, having a contact surface of gradually increasing frictional resistance.
- 15 20. In a sheet separating mechanism, a stationary separating member having a contact surface of gradually increasing frictional resistance, and a reciprocating member having a stronger contact with a sheet than that of said stationary member.
- 20 21. In a sheet separating mechanism, a stationary separator having a frictional surface of gradually increasing frictional resistance, and a reciprocating member having a contact surface which has a frictional resistance greater than that of said stationary separator.
- 25 22. In a sheet separating mechanism, a reciprocating separating member, means for reciprocating said member comprising a reciprocating carriage, guides for said carriage arranged parallel with the sheets, a connecting rod pivoted to said carriage, a crank for driving said connecting rod, and an arm connected with said separating member and adapted to contact with said rod to raise said member during a stroke in one direction.
- 30 35 40 45 50 55 60 65 23. In a sheet separating mechanism, a reciprocating separating member, means for reciprocating said member comprising a reciprocating carriage, a connecting rod pivoted thereto, a crank for driving said connecting rod, an arm connected with said separating member and adapted to be moved by said rod to raise said separating member, a second arm connected with said separating member, and a stop adapted to engage said second arm to limit the downward motion of said separating member.
24. In a sheet separating mechanism, a reciprocating separating member, a carriage therefor, an oscillating part thereon, means for reciprocating said carriage, a spring connected with said part for producing a downward pressure thereon, and a supplementary adjustable spring between said separating member and said part.
25. In a sheet separating mechanism, a reciprocating separating member, a carriage therefor, an oscillating part thereon, means for reciprocating said carriage, means for oscillating said part, a spring carried by said carriage for producing a rotating tension on said part, and a supplementary adjustable spring connected between said member and said part for regulating its pressure.

Signed this 24th day of June, 1909.

RUDOLPH HANAU.
